EDWARD H. WELLS, OF MONTCLAIR, NEW JERSEY, ASSIGNOR TO THE BABCOCK & WILCOX COMPANY, OF BAYONNE, NEW JERSEY, A CORPORATION OF NEW JERSEY.

WATER-TUBE BOILER.

1,080,613.

Specification of Letters Patent.

Patented Dec. 9, 1913.

Application filed April 3, 1912. Serial No. 688,131.

To all whom it may concern:

Be it known that I, EDWARD H. WELLS, a citizen of the United States, residing at Montclair, in the county of Essex and State 5 of New Jersey, have invented certain new and useful Improvements in Water-Tube Boilers, of which the following is a specification.

My invention relates to a water tube boiler, 10 and more particularly to a design comprising two banks of inclined generating tubes, one above the other, the lower bank having its tubes exposed to the direct heat of the furnace and inclined at a different angle to 15 the horizontal than the upper bank, and a chamber above the lower bank, at its lower end, included between the side walls, to form a chamber for the accumulation of dust which may be removed by any suitable 20 means.

In the accompanying drawing, which is a longitudinal section of a boiler embodying my invention, the numeral 1 designates a bank of generating tubes inclined at about 25 thirty degrees to the horizontal and placed directly above the combustion arches 2, so that said tubes shall be exposed to the direct heat of the furnace. The tubes of the bank 1 are expanded into uptake and downtake 30 headers 3 and 4, the sections of the latter being nippled to a cross-box 5, having a blow-off connection 6. Above the tubes 1 is a second bank of inclined generating tubes 7 expanded into uptake and downtake headers 8 and 9. Both banks of tubes are 35 rectangular in cross section. The bank 7 is divided by baffles 10 and 11 into a plurality of transverse passes beginning at the uptake ends of the tubes. The baffle 10 is extended 40 downward to the lower bank of tubes so that the gases pass upward along the lower bank of tubes to the first pass of the upper bank, then downward through the second pass and upward through the third pass to the stack 45 12. The headers 3 and 8 are nippled together, and the headers 4 and 9 are connected by tubes 13 the adjacent sides of which are spaced about three inches apart. The headers 8 and 9 of the upper bank are connected to a steam and water drum 14. A 50 superheater 15 is located in the space above the upper bank of tubes over the first and second passes.

A longitudinal baffle 16 rests upon the upper row of tubes of the lower bank 1, and

extends from the downtake header 4 forwardly to the transverse baffle 10. The baffle 16 forms the floor of a chamber included between the side walls, and the two banks of tubes, forming a chamber in which the dust, which in some cases amounts to about ten per cent. of the total coal fired, may accumulate. This floor may be at an angle a little less than the angle of repose of the material which will lodge thereon. 60 A plate 16' rests against the tubes 13 to form the rear wall of the dust chamber.

The dust may be removed by any suitable means, as for example, a screw conveyer 17 extending through the lower part of the 70 chamber and delivering into ash cars; or the plate 16' and the screw conveyer 17 may be removed and the dust allowed to pass by gravity between the nipples leading downward to the lowermost rear header and be 75 drawn out through chutes. The way in which the dust is removed is immaterial as far as my invention is concerned, and it might be removed by an air suction apparatus instead of a screw conveyer. 80

As shown by me, the entire floor space occupied by the boiler is available as grate area, the furnace being charged through the front and rear doors 18 and 19. A low division wall 20 is shown extending transversely with respect to the furnace between the grate surfaces and forming an air duct opening into both fuel chambers, the openings being controlled by dampers 21. 85

Inclining the lower bank of tubes in the 90 way described allows the cross baffle 11 which separates the last two sections of the upper bank of tubes, to be extended, if so desired, all the way across the bank of tubes. The general baffle arrangement leads to most 95 efficient results as the entire tube surfaces of the boiler are either acted on directly by the radiant heat, or by the hot furnace gases, or are subjected to a cross flow of the gases. In many forms of baffles the gases after 100 leaving the furnace chamber are made to flow in a parallel direction to the tube surfaces, and tests have shown that the absorption of heat with the gases flowing parallel with the tubes is considerably less than when 105 they flow across the tubes.

What I claim and desire to secure by Letters Patent of the United States is:

1. A water tube boiler having two banks of inclined generating tubes one above the 110

other, uptake and downtake headers into which the tubes of said banks are expanded, tubes connecting the downtake headers of said banks, a longitudinal baffle extending 5 from the downtake headers of the lower bank, and a plate resting against said connecting tubes, said baffle and plate forming with the side walls of the setting a dust collecting chamber between the two banks of 10 tubes, and means for removing the dust from said chamber.

2. A water tube boiler having two banks of inclined generating tubes one above the other, uptake and downtake headers into 15 which the tubes of said banks are expanded, tubes connecting the downtake headers of said banks, a transverse baffle extending across the tubes of the upper bank to the lower bank, a longitudinal baffle extending 20 from the downtake headers of the lower bank to said transverse baffle, a plate resting against said connecting tubes, said longitudinal baffle and plate forming with the side walls of the setting 25 a dust collecting chamber between the two banks of tubes, and means for removing the dust from said chamber.

3. A water tube boiler having two banks of inclined generating tubes one above the 30 other, and the lower bank inclined at a greater degree to the horizontal than the inclination of the upper bank, uptake and downtake headers into which the tubes of said banks are expanded, tubes connecting 35 the downtake headers of said banks, a longitudinal baffle extending from the downtake headers of the lower bank, and a plate resting against said connecting tubes, said baffle and plate forming with the side walls 40 of the setting a dust collecting chamber between the two banks of tubes, and means for removing the dust from said chamber.

4. A water tube boiler having two banks of inclined generating tubes one above the other, uptake and downtake headers into 45 which said tubes are expanded, tubes connecting the downtake headers of said banks, transverse baffles dividing the upper bank of tubes into a plurality of passes beginning at the steam uptake end, the baffle at the 50 uptake end being continued to the lower bank of tubes, a longitudinal baffle over the lower bank of tubes extending from the downtake headers to the first transverse baffle, a plate resting against said connecting 55 tubes, said longitudinal baffle and plate forming with the side walls of the setting a dust collecting chamber between the two banks of tubes, and means for removing the dust from said chamber.

5. A water tube boiler having two banks of inclined generating tubes one above the other, uptake and downtake headers into which the tubes of said banks are expanded, said uptake headers being nipped together, 65 tubes connecting the downtake headers of said banks, a transverse baffle extending across the tubes of the upper bank to the lower bank, a longitudinal baffle extending 70 from the downtake headers of the lower bank to said transverse baffle, a plate resting against said connecting tubes, said longitudinal baffle and plate forming with the side walls of the setting a dust collecting chamber between the two banks of tubes, 75 and means for removing the dust from said chamber.

In testimony whereof I have hereunto signed my name in the presence of two subscribing witnesses.

EDWARD H. WELLS.
